UNITED STATES PATENT OFFICE.

FRANK T. ZIMMERMAN, OF AUBURN, INDIANA.

WINDMILL-REGULATOR.

SPECIFICATION forming part of Letters Patent No. 333,806, dated January 5, 1886.

Application filed August 28, 1885. Serial No. 175,580. (No model.)

To all whom it may concern:

Be it known that I, FRANK T. ZIMMERMAN, a citizen of the United States, residing at Auburn, in the county of De Kalb and State of Indiana, have invented certain new and useful Improvements in Windmill-Regulators; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to regulators for windmills used for pumping water, and has special reference to regulating devices which are dependent for their action upon the height of water in a tank into which the mill pumps 20 the water. Certain devices heretofore used for this purpose control the mill by a piston working in a cylinder, the piston being raised by the pressure of water after the latter has reached its maximum height in the tank. To 25 this there are several objections. The piston itself offers such great resistance, by reason of friction, that it is difficult to operate it—in other words, a heavy pressure of water is required to raise the piston, and a counterbalancing-weight is required to return the piston 30 in its downward stroke when the pressure of the water has been removed, in addition to forcing the water out of the cylinder and raising it into the tank—moreover, the frictional 35 resistance of the piston has been found to vary so much in different machines that it is difficult to make a proper adjustment at the factory, and each machine itself varies so much in use that considerable allowance must be 40 made for range of power, in order that the water may at all times raise the piston and the counterbalancing-weight return the same. This is objectionable, for the reason that it is desirable to make the action of the regulator 45 as sensitive as may be. The piston must also necessarily allow the passage of more or less water about its circumference, particularly when slightly worn, thus producing more or less waste or drip into the well, which of 50 course is objectionable, particularly in "drive"

wells, wherein said waste or drip fills the pit of the well.

In practice it has been found that if the piston fits so closely as to allow no leakage, it is too hard to reciprocate, while if it is so loose as to reciprocate freely it will leak more or less.

Another objection to the use of the cylinder and piston aforesaid is the expense and care required in their manufacture. The piston 60 itself must be made with precision and of a smooth rust-proof material, and the cylinder must be made with perfectly-regular walls and composed entirely of a rust-proof material, or be lined with brass, copper, porcelain, or 65 other smooth rust-proof material.

By the use of the devices described below I avoid the above-mentioned objections.

In the accompanying drawings, Figure 1 is a side elevation of my apparatus. Fig. 2 is a 70 detail view of a modification.

A is the pump, having the piston-rod A' extending upward to the wind-wheel.

B is a pipe extending from the pump to the tank D.

C is the regulator.

The reciprocating shaft A' forces the water from the pump through the pipe B and through the valve D' into the tank.

D² is a lever pivoted between its ends, having one end connected with the valve D' and the other with a float, d, which rises and falls as the water in the tank rises and falls. A pipe, c, branches from the pipe B, and has mounted upon its end the bowl-shaped plate, 85 C'. Across this extends a rubber, leather, or other yielding diaphragm, C², and upon this rests in turn a ring, C³, the edges of these three parts being bolted together in such manner as to form a sealed chamber between the plate C' 90 and the diaphragm C². A shaft, c', is arranged perpendicularly to the diaphragm C², and rests thereon with a flattened head. A lever, c², is arranged transversely to the shaft c', and is hinged thereto between its ends in such manner as to make for itself a short arm and a long arm. The short end of the lever c² is hinged to a fixed seat on the regulator. On the opposite side of the regulator is fixed the bracket c⁴, to which is hinged, in the same plane with 95 100

the lever c^2 , a lever, c^3 , having a long arm at its outer end, and a short curved arm at its inner end. To this short inner end the long end of the lever c^3 is joined by means of a link, c^4 , or the two ends of these levers may be connected directly by a slotted joint.

Instead of the hinged connection of the levers just mentioned, I may also use a segment-gear connection, a suitable number of cogs being placed on the end of each lever, as illustrated in Fig. 2.

E is a chain, rope, or wire extending from the outer end of the lever c^3 to the wheel above, where it connects with the usual and well-known devices for throwing said wheel into and out of action.

The operation of the apparatus is as follows: When the water in the tank has reached its maximum height, it lifts the float d and the long end of the bar D^2 , thereby closing the valve D' , whereupon the continued action of the pump causes an increased pressure of the water upon the diaphragm C^2 and presses it upward, thereby raising the shaft c' , levers c^2 , and the short end of the lever c^3 , thus throwing the long end of the lever c^3 downward into the vertical position, and of course drawing the chain or wire E and throwing the mill out of gear. All the apparatus will now be held in this position until the water in the tank D has again been lowered, whereupon the valve D' will again open and allow the water to pass from the pipe B into the tank, thus again decreasing the pressure of water upon the diaphragm C^2 . The elasticity of the diaphragm and the usual action of the wind-governor at the wheel will now restore the diaphragm and the levers connected therewith to their normal position, and again set the wheel and pump into action until such time as the tank shall

again be filled to its maximum height. I thus avoid entirely all leakage of water, while the metallic parts of my device can all be made of common cast or wrought iron without any finishing further than drilling holes for bolts. 45 As there are no sliding parts which are actuated by the force of the water, there is no necessity of careful smoothing or packing, and there is no resistance by reason of friction; neither is there any material difference in the 50 amount of water-pressure required to operate the different regulators made from the same patterns.

I am aware that it is not new to use in devices of this general description a cylinder and 55 piston, and a flexible diaphragm operated by fluid-pressure.

I claim as my invention—

1. The combination, with the pump A, pipe B, tank D, and float-actuated valve D', of the 60 plate C', diaphragm C², shaft c', lever c², lever c³, said levers being connected and operating as described, and wire or chain E, substantially as shown and described.

2. The combination of the pump A and pipe 65 B, connected therewith and communicating at its opposite end with the tank D, having float-valve D', with the plate C', having flexible dia-phragm C² extended across it, the ring C³, the shaft c', and lever c², seated on one side of said 70 ring and plate, and operated by said dia-phragm, and lever c³, connected with lever c² by link c⁴, all combined and operating sub-stantially as described.

In testimony whereof I affix my signature in 75 presence of two witnesses.

FRANK T. ZIMMERMAN.
